His Attorney.

UNITED STATES PATENT OFFICE.

ALLAN H. BACON, OF ST. LOUIS, MISSOURI.

SASH LOCK.

Application filed December 5, 1921. Serial No. 519,824.

To all whom it may concern:

Be it known that I, ALLAN H. BACON, a citizen of the United States, residing at the city of St. Louis, and State of Missouri, have invented a new and useful Sash Lock, of which the following is a specification.

This invention relates to sash locks.

An object of the invention is to provide improved means for locking window sashes in closed position or in different open positions.

Another object of the invention is to provide an improved sash lock comprising a lock device embedded in one of the members 15 of the lower window sash, and a suitable removable key for manipulating the lock device.

Another object of the invention is to provide an improved sash lock comprising a 20 locking device embedded in one of the sash members of the lower window, a suitable key for manipulating said lock device, and a co-operating element embedded in one of the members of the upper sash adapted to be 25 engaged by the lock device carried by the lower sash.

Another object of the invention is to provide improved locking devices for locking the upper and lower windows in closed positions and including a number of locking devices, one of which is manipulative to draw the sash members toward each other and another of which is manipulative to impart pressure tending to force the sashes apart 35 and effective to hold the sashes from movements toward open or closed positions, and suitable keys for manipulating the lock devices.

Other objects will appear from the following description, reference being made to the drawing, in which—

Fig. 1 is a view showing my improved locks applied to a window sash.

Fig. 2 is a cross sectional view on the line 45 2—2 of Fig. 1.

Fig. 3 is a sectional view on the line 3—3 of Fig. 1.

Fig. 4 is a sectional view showing another form of locking device for drawing the 50 sashes together.

Fig. 5 is a view showing the inner face of the outer member of the lock and may be considered as viewed from the line 5—5 of Fig. 4.

55 Figs. 6 and 7 are sectional views showing variations in the form of the lock device

for locking the sashes by frictional engagement.

In the embodiment shown one of the lock devices is embedded in the upper member 60 of the lower window sash and in the lower member of the upper window sash, preferably near the center of the window; while the other lock device is embedded in one of the upper corner portions of the lower window sash.

The locking device that is mounted near the middle of the window sashes is preferably of the construction and arrangement 70 to clamp the two window sashes together and to prevent vertical movement of either window. In the form of such locking device shown in Fig. 2, a barrel 1 is embedded within the upper member of the lower window sash and is formed with a circumferential

75 flange 2 on its inner end which may be seated in a recess in the sash member to form an ornamental escutcheon. Screws 3 passing through holes in the flange 2 and into the upper member of the window sash 80 secure the barrel 1 in position. The inner end of the barrel is closed except for a key-hole 4 through which a key 5 may be inserted and withdrawn. The inside of the outer end of the barrel 1 is provided with 85 threads 6.

The lock bolt shown in Fig. 3 comprises a stem 7 of smaller diameter than the inside diameter of the barrel 1, a threaded body portion 8 for operative engagement with the threads 6, a shoulder or flange 9 rigid with the stem 7 for limiting outward movement of the lock bolt by contact with the threads 6 or any other suitable abutment; and a portion 10 on the inner end of the stem of the lock bolt for engagement by the key 5. It is obvious that the key 5 may be inserted through the keyhole 4 and be engaged with the part 10 of the lock bolt, and that said lock bolt may be operated to or from locking position simply by turning the key.

The cooperating lock element that is embedded in the lower member of the upper sash comprises an internally threaded barrel 11 mounted in an appropriate recess in the sash and secured thereto by screws 12 passing through the holes in a flange 13. The two barrels are so located and arranged that when both windows are closed the barrels are in alignment with each other. 105 Therefore, when the locking bolt is screwed outwardly, the threaded portion 8 thereof 110

leaves the barrel 1 and screws into the barrel 11. Continued rotation of the lock bolt engages the shoulder 9 with the abutment in the barrel 1, after the threaded body portion 8 is out of engagement with said barrel 1 and is entirely within the barrel 11. Further outward movement of the lock bolt is prevented by engagement of the shoulder 9 with the abutment in the barrel 1, with the result that continued rotation of the lock bolt draws or clamps the two window sashes close together.

The variation of this part of the invention shown in Figs. 4 and 5 comprises a barrel 14 embedded within the upper member of the lower window sash, and having a web or wall 15 near its outer end. The lock bolt shown comprises a stem 16 mounted for axial movements through the wall 15 and encircled by a spring 17. The outer end of the spring 17 bears against the web or wall 15 while the inner end of said spring bears against the washer 18 on the inner end of the stem. As shown, a pin 19 passing through the stem 16 serves to hold the washer 18 on the stem and may also serve as a device for engagement with a key whereby the stem may be turned. The outer end of the stem 16 has a lateral projection 20 thereon, the proportion and size of the parts being such that the portion of the barrel 14 outside of the web or wall 15 is of sufficient depth to receive the projection 20 and the outer end of the stem 16 so that the stem will not extend beyond the plane of the outer surface of the sash in which the barrel 14 is embedded.

The cooperating locking element that is embedded in the lower member of the upper sash comprises a barrel 21 having a flange 22 seated in a recess in the lower member of the upper sash and is retained by screws 23. The inner end of the barrel 21 is closed by a wall having a hole 24 therethrough of proper form and size to permit the end of the stem 16 and the projection 20 thereon to pass through the hole 24 into the barrel 21. The inside of the barrel 21 is formed with a spiral flange 25 with which the end 50 of the arm 20 engages. Then when the stem 16 is turned by manipulation of a key or otherwise, the arm 20 will draw the stem 16 outwardly, compressing the spring 17 and serving to draw or clamp the two window sashes together.

The other locking device included in the invention comprises a rotary barrel 26 within a case 27 mounted in a recess near one of the upper corners of the lower sash. The barrel 26 is capable of rotation only by a key 28 insertable into and withdrawable from the barrel through a keyhole 29. The inner end of the barrel 26 is provided with a stem 29^a which is polygonal in cross section and which extends into a hole in a lock

bolt 30. The lock bolt 30 is exteriorly threaded and is screwed in a sleeve 31 so that when the barrel 26 is turned the lock bolt will be moved axially outwardly or inwardly, depending upon the direction in which it is turned by operation of the key. The outer end of the lock bolt is provided with a pad 32 of non-abrasive material, adapted to press against the adjacent member of the upper window sash.

Alternative forms are shown in Figs. 6 and 7. As shown in Fig. 6 the barrel 33 is held stationary within the lower sash and is interiorly threaded. A stem 34 screws into the barrel 33 and is provided with a padded end 35 for pressure against the adjacent member of the upper sash. The inner end of the stem 34 is formed with a key engaging portion 36 whereby said member may be manipulated.

The form shown in Fig. 7 is quite similar to that shown in Fig. 6, except that the end of the stem has a pin 37 for engagement with a key. Other parts being similar to that shown in Fig. 6, similar reference characters are applied thereto.

From the foregoing it is apparent that the locking devices may be cooperatively or independently employed. When the windows are closed both of the locking devices may be used, the one at the center clamping the adjacent cross members of the sashes together and the one at the side being effective to press the window sashes close against the frames in which the sashes are mounted. This prevents oscillation or working of the sashes which might tend to release one or the other of the locks. When the middle lock is released, the windows may be partially opened and locked in any relative position by use of the outer locking device alone.

From the foregoing it will be seen that my invention completely accomplishes all of its intended objects. It is capable of other modifications and forms an ornamental and highly efficient lock.

I do not restrict myself unessentially, but what I claim and desire to secure by Letters Patent, is:—

1. The combination with the adjacent horizontal members of upper and lower window sashes; of a lock for said members comprising a barrel mounted in the horizontal member of the lower sash, threads in the outer end of said barrel opposite the lower horizontal member of the upper sash, a stem mounted in said barrel of smaller diameter than the internal diameter of said threads, an enlarged threaded portion on the outer end of said stem arranged to engage with said threads, a flange near the outer end of said stem arranged to abut against the threads to prevent further outward movement of said stem, a barrel im-

- bedded in the lower horizontal member of the upper sash arranged to be alined with said barrel in the lower sash, threads in said second barrel arranged to engage the threads on said stem, and means for turning said stem to cause the threads thereon to pass wholly out of the first-named barrel and entirely within the second named barrel leaving the unthreaded portion of said stem entirely 5 within the first-named barrel and said flange against the outer ends of the threads in the first-named barrel.
2. The combination with the adjacent horizontal members of upper and lower window sashes; of a lock for said members comprising a barrel mounted in the horizontal member of the lower sash, threads in the outer end of said barrel opposite the lower horizontal member of the upper sash, a 10 stem mounted in said barrel of smaller diameter than the internal diameter of said threads, an enlarged threaded portion on the outer end of said stem arranged to engage with said threads, a flange near the 15 outer end of said stem arranged to abut against the threads to prevent further outward movement of said stem, a barrel imbedded in the lower horizontal member of the upper sash arranged to be alined with 20 said barrel in the lower sash, threads in said second barrel arranged to engage the threads on said stem, means for turning said stem to cause the threads thereon to pass wholly out of the first-named barrel and entirely 25 within the second named barrel leaving the unthreaded portion of said stem entirely within the first-named barrel and said flange against the outer ends of the threads in the first-named barrel, and means for pressing 30 said two sashes in opposite directions against the frame in which they are mounted.
3. A sash lock, comprising two alined barrels one of which is mounted in one sash 35 and one of which is mounted in the adjacent sash, threads on the inside of each of said barrels and extending only a portion of the length of one barrel, a stem mounted 40 in the last-named barrel, threads on said stem for engaging the threads in the barrels 50 and being movable wholly out of the barrel whose threads extend less than the length thereof, and means for effecting a clamping action to draw the sashes together as an incident to the movement of said threads 55 wholly out of one barrel and wholly into the other barrel.
4. A sash lock, comprising two alined barrels one of which is mounted in one sash and one of which is mounted in the adjacent sash, threads on the inside of each of said barrels and extending only a portion of the length of one barrel, a stem mounted 60 in the last-named barrel, threads on said stem for engaging the threads in the barrels 65 and being movable wholly out of the barrel whose threads extend less than the length thereof, means for effecting a clamping action to draw the sashes together as an incident to the movement of said threads 70 wholly out of one barrel and wholly into the other barrel, and means for holding the side edges of the sashes from oscillation.
5. The combination with vertically movable overlapping upper and lower sashes, 75 of locking means for said sashes comprising a central lock composed of two alined threaded barrels one of which is mounted in one sash midway between the side edges of 80 the sash and one of which is mounted in the same relative position in the other sash, a stem mounted in one of said barrels, threads on said stem for engaging the threads in the barrels and being movable wholly out of one barrel into the other barrel, and means 85 for effecting clamping action to draw the sashes together as an incident to the movement of said threads wholly out of one barrel and wholly into the other barrel; and means wholly supported by one of said 90 sashes near the side edge thereof for pressing against the other sash to force the two sashes in opposite directions against the frame in which they are located.

ALLAN H. BACON.
